Attorney

UNITED STATES PATENT OFFICE.

BENJAMIN F. BRILEY, OF SHATTUCK, OKLAHOMA.

WORKBENCH-VISE SCREW.

Application filed February 11, 1927. Serial No. 187,393.

This invention relates to work bench vise screws and has special reference to a novel means for releasing the screw for the quick adjustment and setting of the vise and a means for final adjustment and tightening of the screw when the vise has been set.

I am aware that other means have been provided for the quick adjustment and setting of a vise, of which a common form is an interrupted thread form of screw; but in such a screw only a small amount of movement of the vise is possible when bringing the thread into engagement with the nut, thus requiring that the vise jaws be brought by hand more or less tightly into engagement with the work before setting the vise. In my invention the jaws need be brought only approximately into engagement with the work, the vise set, by means of a releasable locking means, then the jaws clamped into engagement with the work by a final adjustment screw and nut having a considerable amount of movement, the releasable locking means and the final adjustment screw being mounted on a common shaft.

With the above and other objects in view, my invention consists in the combination and arrangement of parts hereinafter described and claimed, and more particularly described in the preferred embodiment illustrated in the accompanying drawings, wherein

Figure 1 is a longitudinal sectional view through a vise having my invention incorporated therein.

Figure 2 is a cross sectional view along the line 2—2 of Figure 1 showing the operating sleeve, the clamp being removed.

Figure 3 is a cross sectional view along the line 3—3 of Figure 1 showing the locking sleeve, the standard being removed.

Referring now more particularly to the drawings, at 10 is indicated the usual standard with which the clamp 11 is adapted to coact in a manner well known to those skilled in the art. A locking sleeve 12 is positioned in the standard 10 by means of a collar 14; said sleeve being provided also with a plurality of ribs as at 13 to prevent rotation of the sleeve in the standard. A locking slot as at 15 is provided longitudinally of said sleeve, and one edge of said slot is formed with a plurality of indentures as at 16. An operating sleeve 17 is journaled in said clamp 11. A collar 18 and a handle 19 are mounted on said sleeve 17 so as to include

said clamp between them. An operating slot 20 is provided in said sleeve 17; the said slot being formed with an offset 21 extending to the end of said sleeve. An interiorly threaded adjustment sleeve 22 having a reduced and solid extension 23 is journaled in said sleeve 17 and adapted to extend through said handle 19, and a lever 24 of the form usual to vises is mounted on said extension 23.

A shaft 25 is positioned in said operating sleeve 17 and adapted to rotate therewith, said shaft being extended through and journaled in said locking sleeve 12. One end of said shaft 25 is adapted to threadedly engage said adjustment sleeve 22 as by threads 26 and the other end of said shaft is provided with a plurality of dogs 27 adapted to engage said indentures 16 provided on said locking sleeve 12. A lug 28 is positioned on said shaft and adapted to engage said operating slot 20 in said operating sleeve 17.

In the use of my invention the operator turns the operating sleeve 17 by means of the handle 19, whereby the shaft 25 is turned by means of the lug 28 engaging the slot 20, and the dogs 27 are thus released from the indentures 16, thereby unlocking the shaft 25 from the locking sleeve 12 as shown in Figure 1. The clamp 11 may now be moved relatively to the standard 10 to suit the work in the vise; when the desired position has been reached, the above described operation is reversed, whereby said shaft 25 is rotated with a right hand turn and is thus locked to the standard 10 against longitudinal movement through the mutual engagement of the dogs 27 with the indentures 16. The final adjustment and tightening of the clamp 11 against the work (not shown) inserted between the clamp 11 and opposed standard 10, is now accomplished by rotating the lever 24, which being rigidly connected to the adjustment sleeve 22, causes the latter to rotate within the sleeve 17 in threaded engagement with the inner end of the shaft 25, whereby the clamp 11 is drawn slowly and powerfully towards the standard 10, thus securing the intervening work.

The purpose of the offset 21 in the slot 20 is to facilitate the mounting of the elements described. If desired, a collar 31 may be formed on the said sleeve 17 so as to be positioned between the said handle 19 and

the clamp 11. A retaining flange 29 is formed on the handle 19 and adapted to engage the shoulder 31 formed on the sleeve 22 whereby the sleeve 22 may be prevented from backing out of the sleeve 17. The handle 19 is set on the sleeve 17 by the set screw 30.

I claim:

10 In combination with a fixed rear standard and an outwardly disposed movable clamp, a vise screw assembly comprising a locking sleeve rigidly mounted through the standard and having a longitudinal locking slot with lateral locking indentures along one margin, 15 an operating sleeve journaled through the clamp in alignment with the said locking sleeve and having an operating slot at its inner end, a handle at the outer end of the operating sleeve, a relatively short adjust-

ment sleeve journaled within the operating 20 sleeve, the inner end thereof being interiorly threaded and its outer end being reduced and extended out through the said handle of the operating sleeve, a lever at the outer end of the adjustment sleeve, a shaft journaled within the said locking and operating sleeves the inner end thereof having a plurality of dogs adapted upon rotation of the shaft to releasably engage the said locking indentures of the locking sleeve and the outer 30 end being threaded to engage the inner end of the adjustment sleeve and having a lug back of the threaded portion adapted to releasably engage the operating slot of the operating sleeve. 35

In testimony whereof I affix my signature.

BENJAMIN F. BRILEY.
